US0D1101148S

(12) **United States Design Patent** (10) **Patent No.:** **US D1,101,148 S**
(45) **Date of Patent:** **** Nov. 4, 2025**

(54) **ORAL SCANNING MODULE**

(71) Applicant: **Matthew M. Stout**, Chappaqua, NY
(US)

(72) Inventor: **Matthew M. Stout**, Chappaqua, NY
(US)

(73) Assignee: **Apollo Innovations, LLC**, Lake Tapps,
WA (US)

(**) Term: **15 Years**

(21) Appl. No.: **29/892,149**

(22) Filed: **May 15, 2023**

Related U.S. Application Data

(63) Continuation of application No. 18/131,020, filed on
Apr. 5, 2023, now Pat. No. 11,744,452.

(57) **CLAIM**

The ornamental design for an oral scanning module as
shown and described.

DESCRIPTION

FIG. 1 is a top, right, front perspective view showing the oral
scanning module;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In the drawings, the broken lines illustrate portions of the
oral scanning module that form no part of the claimed
design.

1 Claim, 5 Drawing Sheets
